MACHINE FOR MAKING WIRE GARMENT HANGERS

David S. Boyles, Rock Hill, S. C., assignor to National Wire Goods Manufacturing Company, Rock Hill, S. C., a partnership composed of David S. Boyles and W. J. Boyles

Application January 6, 1936, Serial No. 57,820

12 Claims. (Cl. 140—71)

The invention has relation to machines for making wire garment hangers, being an improvement upon the machine of my Patent No. 1,941,430, granted December 26, 1933.

5 An object of the invention is to provide means for accomplishing a slight reverse rotation of the means for twisting the shank wires of the hanger to thereby allow for inherent back spring of said wires at the end of the twisting operation and to adapt the twisting means to be properly positioned to receive the shank wires of the next succeeding hanger. Another object is to adapt said twisting means to more readily release the twisted shank wires. Another object is to 15 provide improved means to facilitate the crossing of the end portions of the wire of the hanger prior to bending the same to form the shank wires. Another object is to provide improved 20 means for forming the hanger hook whereby said hook will be centered with respect to the twisted shank and will be as a whole shorter and require less wire, and whereby the hook, which has inherent back spring of the wire thereof after completion of the bending, will be more readily 25 released on reverse rotation of the hook forming head. Another object is to provide means for varying the length of the hangers including adjustable lugs or projections around which the ends of the hanger are bent and to adapt said 30 lugs to be reground and used indefinitely. Other objects and advantages will appear hereinafter.

The invention consists in the novel construction and combinations of parts, as set forth in the appended claims.

35 In the accompanying drawings, Figure 1 is a partial plan view of the machine, showing the wire bending levers in position nearly closed, and the end portions of the wire of the hanger bent to position crossing each other; Figure 2 is a similar 40 view with the wire bending levers in closed position to form the body of the hanger and the end bends of the wire thereof; Figure 3 is a partial plan view showing one end of the machine, parts being broken away, and showing the hook-forming head, the twister head and the operating parts thereof; Figure 4 is an end view of the machine, hidden parts being shown in dotted lines; Figure 5 is a side view of the machine; Figure 6 is a detail plan view, showing the ends 45 of the wire bending levers in closed position and the parallel end bends of the wire of the hanger, parts being broken away; Figure 7 is a similar view, showing the twister head engaging said end bends and the end bends twisted together; Figure 50 8 is a similar view showing the hook-forming

head engaging the longer of said end bends; Figure 9 is a similar view showing the hook-forming head rotated to form the hook, and Figure 10 is a detail side view of the hanger.

The patent aforesaid is referred to for the 5 means for feeding the wire blanks successively to position to the wire bending means; the means for delivering the completed hangers, and for any other necessary means not claimed herein.

In these drawings, the numeral 13 designates 10 the wire blank bending levers, fulcrumed at 14 to the framing, and having upstanding projections 15, which in the operation of said levers take hold of the wire end portions and bend the same around projections or lugs 28 and towards 15 each other to form the shoulder bends of the hanger.

In the present machine, these lugs or projections are elongated and slotted at 281 and are held stationary by means of bolts 282, having 20 clamping nuts thereon which are loosened in making adjustment of the lugs endwise and clamped again in position to hold the adjustment, this endwise adjustment of the lugs providing means for varying the length of the hangers and 25 for taking up wear, so that the lugs may be reground and used indefinitely. The lugs 28 are also reversible end for end in case of need, this facilitating assembly.

In the machine of said patent, when the wire 30 bending levers 13 are moved from the dotted line position to the full line position of Figure 3 of the patent, the end portions of the wire blank are bent around the outer ends of lugs 28 towards each other and are caused to cross each other, 35 and as these wire end portions are precisely held by the wire bending levers, there is more or less opposition of said end portions in the crossing. To facilitate this crossing of the wire end portions, guides therefor are sometimes used.

In the present machine, in order to facilitate 40 such crossing a simpler means is used in that one of said wire end portions prior to crossing the other is engaged with a vertical post 102, to retard the wire end portion, which in the further movement of the wire bending levers is caused to snap past said post and the other wire end portion, the impetus of the movement causing the crossing to be effected the more readily. As shown the post 102 is adapted to deflect the 50 wire end portion engaged thereby slightly laterally and rearwardly so that it may more readily pass the other wire end portion during the crossing.

The twister shaft 56 instead of being rotated 55

by the means of said patent is rotated by the following means:

A train of intermeshed gears comprises pinion 58 of the patent, a lower large drive gear 59, and 5 intermediate gears, pinion 58 being located on the twister shaft 56 as in the patent.

The drive gear 59 is loose on its jack shaft and in order to rotate this gear step by step intermittently and progressively in the same direction 10 the shaft 79 of the patent is extended and provided at its outer end with a rotary arm 60, having a rounded free end engaging successively during successive rotations thereof each of six spaced rollers 61 carried by said drive gear laterally thereof.

In this way each rotation of the arm 60 rotates drive gear 59 one sixth of a rotation, the gear ratio of the train of gears being adapted to thereby rotate the twister shaft 56 two complete 20 turns which is the amount needed to make a double twist in the shank wires of the hanger.

At the end of each one sixth rotation of the drive gear 59, a safety stop lever 62 is operated by its spring 63 to engage its nose between two 25 adjacent of the rollers 61 to thereby intermittently check the rotation of said drive gear; an arm 621 of said stop lever being engaged by rotary arm 60 to disengage the nose of the stop lever from between the two adjacent rollers of the 30 drive gear just prior to engagement of said rotary arm with the next succeeding roller 61. During this movement of the stop lever, its spring 63 is retensioned, and at the end of the movement, the stop lever will be reengaged between the next two succeeding rollers 61.

As it requires slightly more than two turns of the twister shaft to make a double twist in the shank wires of the hanger, due to back spring of 40 the wires after the double twist thereof is completed, a slight reverse rotation of the operating means aforesaid for the twister shaft is provided for, as otherwise the twister head would be left past parallel with the shank wires and would not properly receive the shank wires of the next 45 succeeding hanger, another advantage of said slight reverse rotation being that the twister head 57 is thereby adapted to more readily release the shank wires after the double twist thereof is completed.

50 This slight reverse movement of the operating means referred to is accomplished by pivoted arm 622, the free end of which overlies one of the rollers 61, said pivoted arm being slightly raised at the end portion of each one sixth rotation of drive gear 59 by the underlying roller, to thereby tension the spring 623 of said arm, so that at the end of the one sixth rotation of the drive gear, the pivoted arm will be caused by its tensioned spring to engage the underlying roller and accomplish the slight reverse movement. This reverse movement is limited by contact of said pivoted arm with a stop 624, this contact being retained until the next succeeding roller 61 engages the said arm to again raise the same. The nose of the stop lever 62 engaging between two adjacent rollers 61 is adapted to permit this reverse movement, due to the fact that said nose is slightly narrower than the space between said rollers, thereby providing a space 625 between said nose and the lower of said rollers.

The hook forming means includes a rotary head 64, carrying a roller 65 and a stationary lug 661, the latter having on the side opposed to said roller a flat face 662, said lug having pref-

erably a slot and bolt connection 663 with said head so that it may be adjusted relative to the roller.

In the bending of the hook during rotation of said head, due to the flat face 662 of the lug and the fact that both end roller and the lug have the major portions thereof both located upon one semi-circular half of said head, the arcuate portion of the hook is centered with respect to the shank of the hanger and the hook as a whole is made shorter and requires less wire than the hook of the patent, a further advantage being that the hook, which is subject to a certain amount of back spring after the bending thereof is completed, is released more freely from the said head.

I claim:—

1. In a machine for making wire garment hangers, means for bending successive wire blanks into form including levers having upstanding projections, the machine having cooperating stationary projections around which the wire blank end portions are bent in the operation of said levers; said stationary projections being elongated and slotted and adjustable endwise to make different length hangers.

2. In a machine for making wire garment hangers, means for bending successive wire blanks into form including levers having upstanding projections, the machine having cooperating stationary projections around which the wire blank end portions are bent in the operation of said levers; said stationary projections being elongated and slotted and adjustable endwise to make different length hangers, and also adjustable end for end.

3. In a machine for making wire garment hangers, means for bending successive wire blanks into form including levers having upstanding projections, the machine having cooperating stationary projections around which the wire blank end portions are bent in the operation of said levers to form the shoulder bends in the hanger and to cause said wire end portions to cross each other; said stationary projections being elongated and slotted and adjustable endwise to make different length hangers, and means to facilitate the crossing of said wire end portions comprising means for retarding one of said wire end portions to cause it to snap past the other wire end portion.

4. In a machine for making wire garment hangers, means for bending successive wire blanks into form including levers having upstanding projections, the machine having cooperating stationary projections around which the wire blank end portions are bent in the operation of said levers to form the shoulder bends in the hanger and to cause said wire end portions to cross each other; said stationary projections being elongated and slotted and adjustable endwise to make different length hangers, and means to facilitate the crossing of said wire end portions comprising post means for retarding and deflecting one of said wire end portions to cause it to snap past the other wire end portion.

5. In a machine for making wire garment hangers, means for bending successive wire blanks into form including levers having upstanding projections, the machine having cooperating stationary projections around which the wire blank end portions are bent in the operation of said levers to form the shoulder bends in the hanger and to cause said wire end portions to

- cross each other; and means to facilitate the crossing of said wire end portions comprising post means for retarding and deflecting one of said wire end portions to cause it to snap past 5 the other wire end portion.
6. In a machine for making wire garment hangers, means for bending successive wire blanks into form having parallel straight end bends including levers having upstanding projections, the 10 machine having cooperating projections around which the wire blank end portions are bent in the operation of said levers to form the shoulder bends in the hanger and to cause said wire end portions to cross each other prior to having the 15 straight end bends formed therein, and means for twisting said end bends together comprising a twister shaft and means for rotating said shaft; means to facilitate the crossing of said wire end portions comprising post means for retarding and 20 deflecting one of said wire end portions to cause it to snap past the other wire end portion, said shaft rotating means comprising means for rotating the same intermittently and progressively in the same direction in twisting the end bends 25 of successive hangers.
7. In a machine for making wire garment hangers, means for bending successive wire blanks into form having parallel straight end bends including levers having upstanding projections, the ma- 30 chine having cooperating stationary projections around which the wire blank end portions are bent in the operation of said levers to form the shoulder bends in the hanger and to cause said wire end portions to cross each other prior to 35 having the straight end bends formed therein, and means for twisting said end bends together comprising a twister shaft and means for rotating the same; means to facilitate the crossing of said wire end portions comprising post means 40 for retarding and deflecting one of said wire end portions to cause it to snap past the other wire end portion, said shaft rotating means comprising means for rotating the shaft intermittently and progressively in the same direction in twist- 45 ing the end bends of successive hangers, and means cooperating with said shaft rotating means for rotating said shaft slightly reversely intermediate successive forward rotations thereof to allow for backspring of the twisted end bends.
8. In a machine for making wire garment hangers, means for bending successive wire blanks into form having parallel straight end bends including levers having upstanding projections, the machine having cooperating projections around 50 which the wire blank end portions are bent in the operation of said levers, and means for twisting said end bends together comprising a twister shaft and means for rotating the same; said shaft rotating means comprising means for ro- 55 tating the shaft intermittently and progressively in the same direction in twisting the end bends of successive hangers.
9. In a machine for making wire garment hangers, means for bending successive wire blanks into form having parallel straight end bends including levers having upstanding projections, the machine having cooperating projections around 60 which the wire blank end portions are bent in the operation of said levers, and means for twisting said end bends together comprising a twister shaft and means for rotating said shaft; said shaft rotating means comprising means for ro- 65
- tating the shaft intermittently and progressively in the same direction in twisting the end bends of successive hangers, and means cooperating with the shaft rotating means for rotating the shaft slightly reversely intermediate successive forward rotations thereof to allow for backspring of the twisted end bends.
10. In a machine for making wire garment hangers, means for bending successive wire blanks into form having parallel straight end bends of 10 different lengths including levers having up- standing projections, the machine having coop- erating projections around which the wire blank end portions are bent in the operation of said levers, means for twisting said end bends together 15 comprising a twister shaft and means for rotat- ing the same, and means for bending the extreme end portion of the longer of said end bends into hook form including a rotary head having two spaced projections both of which are eccentric 20 to the axis of rotation of said head; said shaft rotating means comprising means for rotating the shaft intermittently and progressively in the same direction in twisting the end bends of suc- cessive hangers, one of the said projections of 25 said rotary head being a roller and the other of said projections being a stationary lug having a flat face disposed facing said roller.
11. In a machine for making wire garment hangers, means for bending successive wire blanks 30 into form having parallel straight end bends of different lengths including levers having up- standing projections, the machine having co- operating projections around which the wire blank end portions are bent in the operation of 35 said levers, means for twisting said end bends together comprising a twister shaft and means for rotating the same, and means for bending the extreme end portion of the longer of said end bends into hook form including a rotary 40 head having two spaced projections both of which are eccentric to the axis of rotation of said head with the major portions thereof located upon one semi-circular half of said head; said shaft rotating means comprising means for rotating 45 the shaft intermittently and progressively in the same direction in twisting the end bends of suc- cessive hangers, means cooperating with the shaft rotating means for rotating the shaft slightly 50 reversely intermediate successive forward rota- tions thereof, one of said projections of the rotary head being a roller and the other projection being stationary and having a flat face disposed facing said roller.
12. In a machine for making wire garment hangers, means for bending successive wire blanks 55 into form having parallel straight end bends of different lengths including levers having up- standing projections, the machine having coop- erating projections around which the wire blank 60 end portions are bent in the operation of said levers, means for twisting said end bends together, and means for bending the extreme end portion of the longer of said end bends into hook form 65 including a rotary head having two spaced pro- jections both of which are eccentric to the axis of rotation of said head; one of the projections of said head being a roller and the other of said projections being stationary and having a flat face disposed facing said roller.
